UNITED STATES PATENT OFFICE.

WILLIAM DEATS, OF YONKERS, NEW YORK.

AUTOMATIC DISK-FEED.

1,031,694.

Specification of Letters Patent. Patented July 9, 1912.

Application filed September 21, 1910. Serial No. 583,002.

To all whom it may concern:

Be it known that I, WILLIAM DEATS, a citizen of the United States, residing at Yonkers, in the county of Westchester and State of New York, have invented a new and useful Improvement in Automatic Disk-Feeds, of which the following is a specification.

My invention relates to an automatic disk feed mechanism, more particularly described as an automatic device for feeding and withdrawing armature disks or laminations from a punch press.

The principal object of my invention is to provide automatically operable means whereby armature disks are fed to a punch press; thereupon punched, and then stacked on a shaft.

In the accompanying drawings, Figure 1 represents a side elevation of a machine embodying my invention with several parts broken away for clearness; Fig. 2 is a plan view of the same; Fig. 3 is a detail view, partly in section of the turret lifting shaft and one of the disk-holding arms; Fig. 4 is a detail view of a ratchet device on the line 4-4 Fig. 3; Fig. 5 is a detail view on the line 5-5 Fig. 3, showing the suction chambers; Fig. 6 is a detail of the suction and discharge openings of a valve; Fig. 7 is a view of the same rotated; Fig. 8 is a view of the main operating shaft of the punch press; Fig. 9 is a detail view of the disk-feeding device; Fig. 10 is a detail view of the weight compensating device; Fig. 11 is a detail of the ratchet for the same; Fig. 12 is another view of the weight compensating and ratchet devices; Fig. 13 is a modification substantially like Fig. 3 with pressure cylinders for raising and rotating the turret shaft; Fig. 14 is a detail of one of the pressure cylinders; Fig. 15 is a detail view of a trip-cam device of Fig. 1.

Referring now more particularly to Figs. 1 and 2, a standard or base 1 supports at its upper extremity a shaft 6 and the latter carries a drive pulley 5. A slotting device (see also Fig. 8) comprises a sliding head 7, movable up and down in the guides 8; a slotting die 9 is carried by the head 7, and a movable member 10 pressed by springs 11 is to free the die 9 from the punched material. Up and down motion is imparted to the sliding-head 7 by the eccentric 13 mounted on the shaft 6' and secured to the sliding head. Shafts 6 and 6' are not integral and

are connected by the clutch device 14. This clutch device is operated by the foot lever 17 through the rods 15' and 16, connecting the said shafts when the foot-lever 17 is pressed down; the lever being raised by the spring 18.

The arm 2 is secured to the base 1 and supports the die plate 12 which corresponds with the die 9. The arm 2 also supports the 65 turret shaft 4, which in turn supports the turret 3. A disk-rotating shaft 15 is also mounted in the arm 2 and has connections with the shaft 6' intermittently to rotate a toothed wheel 16'. The wheel 16' is operated by cams 19 and 20 (Fig. 8) in connection with the shaft 6', and the rods 21 and 22 (Figs. 2 and 8). Of these rods, 22 is connected to the locking lever 23, while the rod 21 carries the ratchet tooth 24 and is 75 held in position by the arm 25. The locking lever 23 is first moved to release the wheel 16' and thereupon the rod 21 and tooth 24 operate to advance the toothed 80 wheel 16' one step, whereupon the toothed wheel is again locked by the locking lever 23. An adjustable braking device 26 (Fig. 3) is placed about this shaft 15 to prevent the free rotation thereof; and at the upper end of the shaft is a disk-supporting head 85 27 with a centering device 28, locking devices 29, and a spring 30 to allow the said head 27 to give a little.

On the toothed wheel 16' is a pin 31 (Figs. 1 and 2) which engages one end of a lever 90 32 pivoted on the arm 2; the other end of the lever is slotted, the bifurcations extending on either side of a pin 33 which is fastened to a rod 34. This rod extends toward the standard 1 through the locking device 35 and carries a small block 36 with an extending lip 36'; the rod 16 carries a block 37, and when the rod 16 is pressed down the spring 38 causes the rod 34 to move slightly so that the lip 36' extends over the block 100 37 and holds the rod 16 down. The rod 34 also carries a block 39 to engage a clutch-operating device which will be described presently.

An intermediate shaft 41 is directly connected by gears 42 to the main shaft 6 and carries the bevel gear 43. This gear 43 meshes with the gear 44 on the shaft 45 which carries the clutch member 46. A complementary clutch member 47 is mounted on the auxiliary shaft 40 and the clutch device 48 comprises a latch 49 and a two-

armed lever 50, one arm of which is engaged by the block 39 on the rod 34. A cam 51 is mounted on the shaft 40 and engages a roller 52 (Fig. 15) carried by a lever 53 which has one end pivoted to the arm 2, the other end to the rod 54, and the rod is connected with the foot lever 17. A spring 55 is provided to hold the roller 52 in contact with the cam 51.

10 The turret 3 is preferably formed with three projecting arms *a*, *b* and *c*, the turret shaft 4 extending through the hub thereof. This shaft 4 is free to rotate in either direction in the turret hub and has connection 15 with the auxiliary shaft 40. A member 56 (Figs. 1, 2 and 3) is mounted on the shaft 40 and is formed with cam grooves 57 and 58 which extend around the said member. A lever arm 59 on a shaft 64 has a pin or 20 projection which extends into the cam groove 57, and another arm 60 on the same shaft is connected by the link 61 to the toothed rack 62 which meshes with the gear wheel 63 secured to the shaft 4. Another 25 lever arm 65 secured to shaft 67 has a projection which extends into the cam groove 58 and an arm 68 secured to the same shaft 67 has a bifurcated extremity the parts of which extend on either side of the shaft 4 30 and between the shoulders 69. The cam grooves 57 and 58 are shaped to cause the movements of the arms 59 and 65 to effect rotation, raising and lowering of the shaft 4 as the member 56 is intermittently rotated.

35 At the top of the shaft 4 is a ratchet device to rotate the turret 3 (Figs. 3 and 4). A cam-shaped member 70 is keyed to the shaft 4 and has a pawl 71 pivoted thereto and a spring 72 to press the pawl outwardly. In the adjacent portion of the 40 turret 3 there are shoulders 73 with which the pawl engages to rotate the turret 3 when the shaft 4 is rotated.

45 A locking device for the turret 3 is shown in Fig. 3, consisting of a pawl 74 pressed by a spring 75 and supported by a projecting portion of the main arm 2. In the under face of the turret 3 are openings into which the pawl 74 is pressed by the spring; 50 one opening 76 for each turret arm. To free the turret of the locking device it, the turret, is lifted up before the device which operates the same is rotated. A retarding device or brake 77 is provided for the shaft 55 4 to prevent unsteady or free movement thereof. This device is too well known to require further description.

60 Referring again to Fig. 1, an adjustable bracket 78 is shown bolted to a projecting portion 2' of the main arm 2. The bracket carries blocks 81, 82, having notches in their opposing faces. The blocks are adjusted to and away from each other. A right and left threaded bolt 83 with the head 84 (see also 65 Fig. 2) is to adjust the distance apart of

the notched blocks between whose faces the shaft 79 is stepped upright.

On another arm 85, projecting from the main arm 2 is the disk feeding device. The feeding device arm, the disk receiving bracket, 70 and the main arm are equidistant from each other to correspond with the three equidistant arms of the turret 3. Details of the disk feeding device are shown by Figs. 9, 10, 11 and 12. A stack of disks 86 with a central shaft opening and centered by a longitudinally slotted shell shaft 87 are held up by a plate 88, cross piece 89, and shaft 90. The shaft 90 is free to move up and down within the shell shaft 87, and carries the 80 plate 88 on the cross piece 89, and is provided with a toothed rack 91 to move the shaft up and down. A weight 92 is suspended by a flexible cable 93 from the irregularly shaped cam 94 mounted on the shaft 85 95 to which the gear wheel 96 is fixed. Gear wheels 97 and 98 are fixed to the shaft 99, the former meshing with gear wheel 96 and the latter with gear wheel 100 on shaft 101 and with the rack 91 on the shaft 90. A 90 ratchet wheel 102 is also secured to shaft 101, and the ratchet pawl 103 to engage the wheel 102 is pivoted to the lever 104, the latter being pivoted to the arm 85, and the rod 105 to the lever 104. The locking pawl 95 106 is pressed by a spring 107 to engage the ratchet wheel 102. The rod 105 is connected to a pin 108 in the disk 109 which is at the end of the auxiliary shaft 40. Although a spring 110 presses against the ratchet pawl 100 103, it is held out of engagement by an arm 111 on the rod 112. An arm 113 is secured to the upper portion of the rod 112, and a hinged end 114 of the arm is pressed down by spring 115. The hinged end 114 of the 105 arm is pressed against the stack of disks 86 by the spring 116, and when a certain number of disks are removed from the top the arm 113 is rotated over the stack of disks 86. This causes the arm 111 to be rotated in 110 such a manner that the ratchet pawl 103 is released and engages the ratchet wheel 102; the movement of the rod 105 causes the ratchet wheel 102 and the shaft 101 to be rotated, and through the geared connections 115 to raise the stack of disks 86 and to lower the weight 92. Raising the disks raises the hinged arm 114 which has swung over the disks, and before the next disk is picked off the disk stack the turret 3 rotates and is 120 lowered. A pin 117 with a beveled edge is fastened on the turret and strikes the arm 113 as the turret is lowered, causing the arm to be moved over in its first described position ready for another operation, and at 125 the same time forcing the pawl 103 out of engagement with the rotated wheel 102.

In each of the turret arms *a*, *b*, and *c* are passages or ducts 118, (Fig. 3) which lead from the hub to the outer end of the arm; 130

a valve 119 is secured to the turret shaft 4, as is also a plate 120 with an exhaust opening 121. An opening 122 communicates with the interior of the casing of the turret shaft 4 and a reduced portion 123 of the shaft and the opening 124 complete a passage to the longitudinal duct 125 in the shaft 4. An opening 126 connects the duct 125 with the suction port 127 of the valve 119. The suction port 127 is of such a length that it embraces two of the ducts 118 at the same time. The exhaust port 128 is of a length to embrace one of the ducts 118 and the exhaust opening 121 in the plate 120 when the turret is in one of its stop positions. The end or head of each arm supports a shaft 129 which has a ball bearing 130 to allow free rotation and a coil spring 131 presses the shaft downwardly. This shaft has a suction head 132 with chambers 133, a plurality of suction chambers 135, (see Fig. 5) opening on the bottom face adjacent a disk 136, openings 134, connecting chambers 133 and 135 and passages 137 to connect the chambers 133, 135 with the duct 138 in the shaft 129. About the shaft 129 near the duct 118 is an enlarged opening 139. A passage 140 connects the duct 138 in the shaft 129 with the opening 139, and it is evident that when the valve 119 is in a certain position an airtight passage way is completed from the opening 122 in the shaft casing through the turret shaft 4, arm ducts 118 to the suction openings 135. Around the edges of these latter openings 135 are grooves which contain or hold a strip of material 141 such as rubber. This material makes better contact with the disks than the metal edges of the suction chambers. A plurality of chambers 135 is provided so that if airtight connection is not made with the disk by one or more of the chambers, the others will have sufficient strength to hold the disk. An air pump is continuously connected to the opening 122, and the valve 119 is automatically varied to complete the opening to atmospheric pressure by way of the exhaust opening 121 as well as the air suction passageway. A disk centering device is located in the head 132 which comprises a round member 142 with a projecting piece held in the head by the set screw 143, a spring 144 pressing it downwardly to center the disk when it is picked up off of the supply stack by the air suction.

A modified form and method of operating part of my machine is shown by Fig. 13. This is similar for the most part to Fig. 3, with the exception that the shaft 4' is rotated, raised and lowered by the pressure devices 145, and 146. These are governed by valves 147 and 148 respectively and the valves are operated by the arms 59' and 65' which are similar to the arms 59 and 65 of Fig. 3. The turret 3' contains pneumatic ducts, and rotates intermittently, as does turret 3, but is not raised and lowered. The shaft 4' extends through the turret 3' and supports the auxiliary turret arms d, 70 e, f. The shafts 129' are secured in the said arms d, e, f, and pass through the ends of the arms a', b', c' to support the suction heads 132'. By this arrangement the turret 3' which contains the air duct is not 75 raised and lowered, the shaft 4' does not have an air duct and the valve 119' is located in the stationary casting 149.

Fig. 14 shows a detail of one of the pressure devices, comprising a cylinder 152, 80 piston 154, piston rod 153, valve rod 150, pressure opening 151 and exhaust opening 155.

In order that the preferred form of my invention may be more readily understood, 85 the operation will be set forth in detail.

Assuming that the driving pulley 5 is being rotated, the machine is started by pressing the foot-lever 17 to apply the clutch device 14; this causes the shaft 6' 90 to be rotated, the rod 34 being pressed over by the spring 31 to lock the rod 16 in its downward position by means of the block 36. The toothed wheel 16' is moved around by the ratchet tooth 24 until the pin 31 95 strikes the lever 32; the lever moves the rod 34 releasing the rod 16 and the clutch device 14 and applying the clutch 48. This clutch causes the auxiliary shaft 40 to be rotated by means of a gear wheel connection with the intermediate shaft 41 which is directly connected to the main shaft 6. When the toothed wheel 16' is being rotated the turret 3 is in its lowermost position 100 so that the suction head on the arm c rests on the stack of disks 86 which is held by the arm 85; the valve 119 is then in the position shown by Fig. 6 and the port opening 127 completes a suction passageway from the suction chambers 135 in the turret 110 arm c to the air pump opening 122, causing a single disk to be picked up and held. As the auxiliary shaft 40 is rotated the irregular groove 58 in the member 56 causes the lever arm 65 to move and through its connections to raise the shaft 4, the turret 3 and with it the disk. The shaft 4 is then rotated one-third of a revolution by the rack 62 which is operated by means of the arm 56 and the irregular groove 57. Rotation 115 of the shaft 4 causes the turret 3 to be rotated by the ratchet 71. The locking pawl 74 engages in one of the openings 76 to stop the arm c in the next position, the irregular slot 58 being so formed that the turret 3 120 and the shaft 4 are lowered after they have been advanced one step. Before the turret is rotated the suction port 127 and the arm c are in the position shown by Fig. 6; when the turret and shaft are rotated the valve 130

119 rotates with them and takes the position shown by Fig. 7. The shaft 4 is then rotated in the reverse direction one third of a revolution until the valve 119 takes the 5 position shown in Fig. 6. The disk held by the suction head is lowered upon the disk holding head 27, the edge of the disk resting on the die plate 12 beneath the slotting die 9. The cam 51 on the shaft 40 is operated to push down on the rod 54 attached to the foot lever 17 at substantially the 10 same time the clutch 48 is released, thus stopping the shaft 40 and setting the slotting device and disk rotating shaft 15 in motion to slot the edge of the disk. 15 Automatic stopping of the slotting device and starting of the turret rotative means is effected in the same way as previously set forth, the succeeding arm *b* picking a disk 20 off the disk stack. The slotted disk is still held by the suction head and the arm *c* is rotated to the position of arm *b* in Fig. 1, directly over the receiving shaft 79. When the valve 119 is again reversed, the 25 air pump connection through port 127 is cut off and the port 128 opens a passageway from the suction head in the arm *c* through the opening 121 to atmospheric pressure. This releases the disk and it 30 drops upon the shaft 79. The next step or rotation of the turret 3 rotates the arm *c* to its original position while another disk is picked up and the same operation repeated. Since the turret arms are all similar the operation of all of them is alike, and it is evident that this operation is continuous and automatic. The operation of 35 the disk feeding device in which the position of the weight 92 is varied to balance the stack of disks 86 has been explained.

To stop the machine it is necessary only to release the rod 16 from its pressed down position by moving the rod 34, the spring 18 forcing it upward. The clutch device 48 45 automatically releases after one revolution of shaft 40, so if the disk rotative shaft 15 is not operated the shaft 40 will not be actuated and the machine stops at the proper time.

50 It is seen that the operation of the machine is entirely automatic from start to finish, it being necessary only to supply the blank disks and to remove them, slotted and stacked upon the armature shaft. The machine is readily adapted for different sized disks or slots. It is of course evident that those skilled in the arts to which this invention appertains may make various changes in the construction, combination and arrangement of the several parts without departing from the spirit and scope of the invention.

55 What I claim and desire to secure by Letters Patent of the United States is:—

60 1. In a unitary machine, the combination

of a punch press to punch disks, pneumatic means to pick up and hold a disk and mechanical means operable while the disk is thus held to feed the same to and remove the same from the press.

2. In a unitary machine, the combination 70 of a punch press to punch disks, pneumatic means to pick up a disk, and mechanical means to feed the same to and remove the same from the press, the pneumatic means 75 acting to hold the disk throughout the operations of the feeding and removing the same from the press.

3. In a unitary machine, the combination 80 of a punch press to punch disks, pneumatic means to pick up a disk, mechanical means to feed the same to and remove the same from the press, the pneumatic means acting to hold the disk throughout the operations 85 of the feeding and removing the same from the press, and means to release the disk from the pneumatic means.

4. In an automatic disk slotting machine, the combination of pneumatic means for picking up and holding disks, means for 90 feeding the same to and rotating the same beneath the slotting members and away therefrom when slotted, and means for releasing the disks at a given place.

5. In a disk slotting machine, the combination 95 of a slotting device, a revoluble turret having projecting arms, means in conjunction with each arm for picking up and holding a disk, a device for intermittently rotating the turret, and means for rotating a 100 disk beneath the slotting device while held by said holding means.

6. In a disk slotting machine, the combination 105 of a vertically movable turret with projecting arms, pneumatic means in each arm for picking up and holding a disk, a rotatable shaft supporting the turret, and means in connection with the shaft for raising the turret, mechanism for rotating the turret, and slotting mechanism operable to 110 slot the disk while held by said pneumatic means.

7. In a disk feeding and slotting machine, the combination 115 of main operating shafts therefor, an auxiliary shaft, a revoluble vertically movable turret for feeding the disks, means in conjunction with the said auxiliary shaft for raising, lowering and rotating the turret, and an automatic clutch device to connect the said auxiliary shaft to a main 120 operating shaft.

8. In a disk feeding and slotting machine, the combination 125 of main operating shafts therefor, an auxiliary shaft, a revoluble vertically movable turret for feeding the disks, means in conjunction with the said auxiliary shaft for raising, lowering, and rotating the turret, and an automatic clutch device intermittently operable to connect the said auxiliary shaft to a main operating shaft.

9. In a disk feeding and slotting machine, the combination of a revoluble vertically movable turret, main and auxiliary shafts, levers intermittently operated by an auxiliary shaft to raise, lower and rotate the turret, means to support disks on the turret during such movements, locking devices to lock the turret in certain positions, and means to slot the disks while the turret is locked. 10. In a disk feeding and slotting machine, the combination of a revoluble vertically movable feeding turret, main and auxiliary shafts, a slotted member mounted on an auxiliary shaft, a lever guided by one of said slots and operative intermittently to rotate the turret, and another lever guided by another slot and operative to raise the turret before the rotating lever is operated and to lower the turret after it has been rotated. 11. In a disk feeding and slotting machine, the combination of a revoluble vertically movable feeding turret, main and auxiliary shafts, a slotted member mounted on an auxiliary shaft, a lever guided by one of said slots and operative intermittently to rotate the turret, openings in the under side of the turret, a spring-pressed pawl to engage therein and to lock the turret after an intermittent rotation, and a lever guided by a slot in the slotted member operative to raise the turret clear of the locking pawl before the rotating lever is operated and to lower the turret after it has been rotated and locked against further rotation. 12. In a disk feeding and slotting machine, the combination of a revoluble feeding turret, a vertically movable shaft for supporting the turret, main and auxiliary driving shafts, levers in connection therewith and operated thereby to effect the raising, lowering and rotation of the turret shaft and the turret, and a braking device about the said turret shaft. 13. In a disk feeding and slotting machine, the combination of a revoluble feeding turret, a main shaft, an auxiliary shaft, means to connect the main and auxiliary shafts, devices in connection with the latter to rotate the said turret step by step, means in connection with the main shaft to rotate a disk under the slotting device independently of the rotation of the turret, and means operated by the auxiliary shaft to automatically set the disk rotative means in operation when the turret has been rotated one step. 14. In a disk feeding and slotting machine, the combination of a revoluble feeding turret, a main shaft, an auxiliary shaft, means to connect the main and auxiliary shafts, devices in connection with the latter to rotate the said turret step by step, means in connection with the main shaft to rotate a disk under the slotting device independently of the rotation of the turret, and automatic means in conjunction with the disk rotative device to lock the slotting device and to effect the rotation of the auxiliary shaft. 15. In a disk feeding and slotting machine, the combination of a revoluble feeding turret, a main shaft, an auxiliary shaft, means to connect the main and auxiliary shafts, devices in connection with the latter to rotate the said turret step by step, means in connection with the main shaft to rotate a disk under the slotting device independently of the rotation of the turret, means automatically operated by the disk rotative device after one complete revolution thereof to lock the slotting device and the disk rotative means and to effect the rotation of the auxiliary shaft after one revolution and effective to set the slotting device and the disk rotative device again in operation. 16. In a disk feeding and slotting machine, the combination of a main shaft, an auxiliary shaft, a geared shaft connected to the main shaft, a single revolution clutch operative to connect the geared shaft and the auxiliary shaft, a feeding turret rotated by the auxiliary shaft, disk rotative and disk slotting means operated by the main shaft, a clutch to render operative the last named means, a foot lever initially to operate the said clutch, a slidale rod carrying a cam and a locking nut to keep the foot lever and the clutch in position, a lever to control the rod, a pin carried by the disk rotative means and operative to engage the lever to operate the single revolution clutch and to release the other clutch, and a cam device in connection with the auxiliary shaft automatically to again operate the foot lever when the said shaft has made one revolution. 17. In a disk feeding and slotting machine, the combination of a feeding turret with projecting arms, a main shaft, an auxiliary shaft, means operated thereby to rotate the turret step by step, disk rotating and slotting mechanisms, means to automatically operate the said mechanisms alternately with the turret rotative means, ducts in the said arms, and a valve to provide pressure and exhaust connections for the said ducts. 18. In a disk feeding and slotting machine, the combination of a feeding turret with projecting arms, a main shaft, an auxiliary shaft, means operated thereby to rotate the turret step by step, disk rotating and slotting mechanisms, means automatically to operate the said mechanisms alternately with the turret rotative means, ducts in the said arms, and a valve operated as the turret is rotated. 19. In a disk feeding and slotting machine, the combination of a feeding turret

with projecting arms, a main shaft, an auxiliary shaft, means operated thereby to rotate the turret step by step, disk rotating and slotting mechanisms, means automatically to operate the said mechanisms alternately with the turret rotative means, ducts in the said arms, and a valve operative to provide a vacuum port for two periods and an exhaust port for one period in succession for the duct in each of the arms.

20. In a disk feeding and slotting machine, the combination of a feeding turret with projecting arms, a shaft to support the turret, a main shaft, intermediate connections between the said shafts, means to rotate the turret intermittently in one direction and the turret shaft in both directions, pressure ducts in the turret arms, and a valve reciprocated with the turret shaft and operative to provide pressure and exhaust port openings for each of the ducts in alternate succession.

21. In a disk feeding and slotting machine, the combination of a feeding turret with three arms, pressure ducts in the arms, a shaft to support the turret, a main shaft, intermediate connections between the said shafts, means to rotate the turret intermittently in one direction one third of a revolution at each step and to rotate the turret shaft in both directions, a duct in the turret shaft, and a valve operated by the turret shaft and coöperating with the duct in the turret shaft to provide different port openings for the ducts in the turret arms.

22. In a disk feeding and slotting machine, the combination of a feeding turret with three arms, pressure ducts in the arms, a shaft to support the turret, a main shaft, intermediate connections between the said shafts, means to rotate the turret intermittently in one direction, a duct in the turret shaft, an air exhausting connection with the said duct, and a valve operated by the turret shaft and effective to provide connections to exhaust air from the arm ducts and to admit air thereto at atmospheric pressure.

23. In a disk feeding and slotting machine, the combination of a feeding turret with three arms, pressure ducts in the arms, a shaft to support the turret, a main shaft, intermediate connections between the said shafts, means to rotate the turret intermittently in one direction, a duct in the turret shaft, an air pump connection thereto, an atmospheric inlet opening and a valve in connection with the turret shaft operative to maintain a passage simultaneously between the air pump and two of the arm ducts and between the other arm and the said inlet opening.

24. In a disk feeding and slotting machine, the combination of a feeding turret with projecting arms, pressure ducts in the arms extending from the hub to the end of

the arm, suction chambers at the end of each arm having a passage communicating with the said ducts, air pump and exhaust connections, and a valve operated as the turret revolves to provide air pump and exhaust connections for the said suction chambers.

25. In a disk feeding and slotting machine, the combination of a feeding turret with projecting arms, pressure ducts in the arms extending from the hub to the end of the arm, suction chambers, a member freely rotatable and movable up and down in the arms, supporting said chambers and providing a passage from the duct to the said chambers, and means automatically to change port openings to the said ducts.

26. In a disk feeding and slotting machine, the combination of a feeding turret with projecting arms, pressure ducts in the arms extending from the hub to the end of the arms, suction chambers, a member freely rotatable and movable up and down in the arm supporting said chambers and providing a passage from the duct to the said chambers, and a centering device for disks carried by the said member.

27. In a disk feeding and slotting machine, the combination of a feeding turret with projecting arms, pressure ducts in the arms extending from the hub to the end of the arm, suction chambers at the end of each arm having a passage communicating with the said ducts, air pump and exhaust connections, means for intermittently rotating the turret step by step, a valve, means to reciprocate the valve, and means coöperating with the valve to automatically connect the air pump to one of the suction chambers to pick up a disk and hold the same while the turret is rotated and to open the exhaust connection when the disk has been rotated to a predetermined position.

28. In a disk feeding and slotting machine, the combination of a three armed feeding turret, a disk feeding stack, a disk discharge receiver, pneumatic ducts in the turret arms, mechanical means for intermittently rotating the turret, suction and discharge connections for the ducts, a valve to provide ports for the said connections, and means automatically to pick up a disk from the disk feeding stack by one of the arms by suction and to hold the same while the arm is rotated two steps and then to drop the disk upon the discharge receiver.

29. In a disk feeding and slotting machine, the combination of a disk feeding stack, and a disk discharge receiver equally disposed with respect to the slotting device and to each other, a three armed vertically movable and revoluble turret, pneumatic passages in the arms, pneumatic suction chambers at the ends of the arms having connection with the said passages, mechanical means for raising, rotating and

lowering the turret, air pump and air inlet connections, a valve to provide openings between the said passages and the said connections, and automatic mechanical means 5 to operate the valve for one arm to pick up a disk from the feeding stack, hold the disk while the turret is raised, rotated and lowered, and the disk slotted, then raised, rotated and lowered with the turret, and the 10 valve changed to the air inlet opening to allow the disk to drop on the discharge receiver.

30. In a disk feeding and slotting machine, the combination of a feeding turret 15 with projecting arms, mechanical means intermittently to rotate the turret, mechanism to slot the disks, a discharge receiver for slotted disks, means for stacking the disks on said receiver, a disk feeding device, and 20 means automatically to raise the disks on the feeding device.

31. In a disk feeding and slotting machine, the combination of a feeding turret with projecting arms, mechanical means 25 intermittently to rotate the turret, a receiver for slotted disks, an arm projecting from the machine, a shaft to support a stack of blank disks mounted in the said arm, and means automatically to raise the blank disks to 30 keep the top disk within prescribed limits.

32. In a disk feeding and slotting machine, the combination of a feeding turret with projecting arms, mechanical means intermittently to rotate the turret, a receiver 35 for slotted disks, an arm projecting from the machine, a shaft to support a stack of blank disks mounted in the said arm, a compensating weight device to balance the disk stack, and means automatically to vary the 40 balancing weight in accordance with the height of the disk stack.

33. In a disk feeding and slotting machine, the combination of a feeding turret, main and auxiliary shafts, means in connection with the latter automatically to rotate 45 the said turret, a disk holding device to supply disks to the turret, a balancing device therefor automatically variable to compensate for removed disks, and means in 50 connection with the said auxiliary shaft positively to operate the said device.

34. In a disk feeding and slotting machine, the combination of a feeding turret, main and auxiliary shafts, means in connection with the latter automatically to 55 rotate the said turret, a disk holding device to supply disks to the turret, a balancing device therefor to compensate for removed disks, a ratchet device to operate the balancing device from the auxiliary shaft, and means automatically to effect the operation 60 of the said ratchet device when a prescribed number of disks have been removed.

35. In a disk feeding and slotting machine, the combination of a feeding turret, 65

main and auxiliary shafts, means in connection with the latter automatically to rotate the said turret, a disk holding device to supply disks to the turret, a balancing device therefor to compensate for removed 70 disks, a ratchet wheel for the balancing device, a ratcheting device connected with the auxiliary shaft, and a rod with levers one to swing over the stack of disks when a prescribed number are removed, another to hold 75 the ratcheting device out of engagement with the ratchet wheel until the first lever swings over the stack of disks.

36. In a disk feeding and slotting machine, the combination of a feeding turret, 80 main and auxiliary shafts, means in connection with the latter intermittently to rotate the turret, and a disk holding device comprising a longitudinally slotted shell shaft, a shaft movable within the shell shaft 85 carrying a disk supporting head and provided with a toothed rack, a weight to balance the weight of the disks, a cam having a varying radius to support the weight, gear wheels connecting the cam and the said rack and means automatically to rotate the gear wheels to raise the movable shaft and to rotate the said cam to vary the weight in accordance when disks are removed from 90 the stack.

37. In a disk feeding and slotting machine, the combination of a feeding turret, main and auxiliary shafts, means in connection with the latter automatically to rotate the said turret, a disk holding device 100 to supply disks to the turret, a balancing device therefor to compensate for removed disks, a ratchet wheel for the balancing device, a ratcheting device connected with the auxiliary shaft, and a rod with levers one 105 hinged and a spring attached thereto to swing the lever over the stack of disks when a prescribed number of disks are removed, another lever to hold the ratcheting device out of engagement with the ratchet wheel 110 until the hinged lever swings over the stack of disks, automatic means thereupon operative to raise the disks and the hinged lever, and pins attached to the turret to engage the lever and to return the same to its first position.

38. In a disk feeding and slotting machine, the combination of a slotting device, a revoluble feeding turret therefor, a disk holding supply device, pneumatic means in connection with the turret, automatically operable to pick up a disk and hold the same during the operation thereon of the slotting device, an adjustable receiver support comprising an arm, and a shaft supporting holder adjustable for different sized shafts, and means whereby the pneumatic pressure holding a disk is released at a predetermined time to drop the disk.

39. In a machine of the character de- 130

scribed, the combination of mechanism for slotting the periphery of a disk, means to hold a supply of disks, and means operable automatically to carry the disks to the slotting mechanism, effect the operation of said mechanism and remove and stack the slotted disks.

40. In a slotting machine, the combination of a holding punch, a rotatable turret, 10 a disk holder rotatably mounted in the turret, means for rotating the turret and carrying each disk into position to be operated upon by the punch, and mechanism for intermittently rotating said holder and 15 operating the punch.

41. In a slotting machine, the combina-

tion of a rotatable turret, a pneumatic disk holder rotatably supported by the turret, means to cause said holder to pick up a disk, a slotting punch, means for rotating the turret and transferring the disk to a position beneath the punch, and means for imparting a step by step rotation to the said holder and disk and operating the punch while the disk is held by said holder. 20 25

In testimony whereof, I have signed my name to this specification in the presence of two subscribing witnesses.

WILLIAM DEATS.
